FILM PROCESSOR

Verneur E. Pratt and George F. Gray,
Norwalk, Conn.

Application December 23, 1947, Serial No. 793,360

10 Claims. (Cl. 95—94)

1

This invention relates to improvements in film processors, and has for an object the provision of a processor for film or other light-sensitive coated strips adapted to automatically develop, fix, wash, and dry the strips and roll them up again ready for use. Such a machine makes it unnecessary to have to employ a skilled technician to operate the machine.

Another object of the invention is the provision in a film processor of an array of U-shaped tubes which constitute the tanks for containing the processing fluids and through which the exposed light-sensitive strip is passed.

Yet another object of the invention is the provision in a film processor of the character described, and means for circulating the processing fluid in the individual U-shaped tubes, said means including a pump the outlet of which delivers the fluid to a manifold adjacent to the inlet end of one leg of the U-shaped tube, and the provision of an overflow catcher adjacent to the open end of the other leg of the U-shaped tube, the further provision of a small tank or sump into which the bottom of the U-shaped tube extends, said tank or sump being adapted to catch the fluid overflowing from said tube, and the provision of a connection between said sump and the inlet of said pump so that the pump continuously circulates processing fluid through the U-shaped tank.

Another object of the invention is the provision in a device of the character described, of a U-shaped tube which is the last in a series which constitutes the washing tank in which the film is washed, the inlet end of said tube having a plurality of perforations therein and communicating with the interior of a manifold, connections between said manifold and a source of water, said manifold extending from one leg of the U around the bottom and embracing a substantial portion of the other leg of the U, said manifold terminating in a tank-like vessel having a drain connected thereto and valved so that water is discharged therefrom via said drain when a predetermined level in the vessel has been reached by the water.

Yet another object of the invention is the provision in a film processor of roller means adjacent to and meeting along a line above the open end of the inlet leg of the first U-shaped tube in the array, said roller means being adapted to remove film from a reel and deliver it to the first U-shaped tube in said array, other roller means engaging the film between adjacent legs of others of the U-shaped tubes in said array for guiding the film from the exit leg of one U-shaped tube to the inlet leg of the succeeding one, and the

2

further provision of roller means which include a drive roller and a free roller urged in squeegeeing relation with the drive roller above the exit leg of the washing tube for squeegeeing excess water from the film strip before it enters a drier.

Other objects and advantages of the invention will be apparent to those skilled in the art and upon a study of the specification and the accompanying drawings.

10 Referring to the drawings:

Figure 1 is a side elevation partly in section of a complete processor;

Figure 2 is a plan view taken along the lines 2—2 of Figure 1, and showing the arrangement for driving the drive rollers;

Figure 3 is an elevation taken along the lines 3—3 of Figure 1;

Figure 4 is a sectional view of one of the U-shaped tubes taken along the lines 4—4 of Figure 1;

Figure 5 is a cross sectional elevation taken along the lines 5—5 of Figure 1; and

Figure 6 is an enlarged detailed view of the film pickup device.

25 Referring first to Figure 1, the processor is housed in a cabinet 10 which has a closable door, not shown. The door is omitted in Figure 1 to reveal the entire interior of the casing, and what is seen in Figure 1 would be seen when the door is open.

The cabinet has an intermediate wall 11 (see also Figure 2). Journaled in a bearing bushing on the wall 11 is a stud shaft 12 upon which the reel of film 13 to be developed, is supported. Behind the wall 11, in spaced relation thereto, is a support plate 14. A bracket 15 has a shaft 16 therein journaled in bearing holes formed in the supports 11 and 14. The bracket 15 has formed integral therewith a lateral arm portion 17 and the boss 18 which extends through the arcuate hole 19 formed in the supporting wall 11. Journaled on the boss 18 is a free roller 20 having a rim 21 thereon formed of rubber-like material. A bearing bushing 22 is pressed into a hole in the supporting wall 11, and a like bushing 23 is pressed into a hole in the support 14 in alignment with the bushing 22. A shaft 24 is journaled in the bearings 22 and 23, and has secured thereto a worm gear 25, the gear being fixed on the shaft by means of a pin 26 extending through the hub thereof and through the shaft.

A collar 27 pinned to the shaft 24 abuts the bushing 23, and a like collar 28 is pinned to the shaft 24 and abuts the bushing 22 thereby eliminating end play. The shaft 24 is stepped and supported on the stepped portion is a backing

55 55

washer 29 and a roller 30 which is secured thereon by means of a screw 31 engaging an axially threaded hole in the shaft. The roller 30 has a rim 32 of rubber-like material.

In lateral alignment with and spaced apart from the bearing bushing 22 is a bearing bushing 33 which is pressed into a hole formed in the supporting wall 11. A like bushing 34 is pressed into a corresponding hole in the support plate 14 so that it is in alignment with the bushing 33. A shaft 35 is journaled in the bushings 33 and 34 and carries a worm gear 36 which is secured to the shaft by means of a pin 37 extending through its hub and through the shaft. A collar 38 pinned to the shaft 35 abuts the bearing 34 and a like collar 39 pinned to the shaft abuts the bearing 33. The shaft 35 is stepped, and mounted on the stepped portion is a backing washer 40 and a roller 41 which are secured to the shaft by means of a screw 42. The roller 41 has a rim 43 of rubber-like material. The supporting wall 11 and the support plate 14 also carry, in spaced relation to the bearing 33, aligned bearing bushings 44 and 45 respectively, and journaled in these bearing bushings is a shaft 46 which has pin collars 47 and 48 respectively abutting the bearings 44 and 45. The shaft also has a worm gear 49 thereon which is keyed thereto by a pin 50. The shaft 46 on its outer end is stepped, and mounted on the stepped portion is a backing washer 51 and a roller 52 which are secured on the shaft by means of a screw 53. The roller 52 also has a rim 54 of rubber-like material. The supporting wall 11, and the support plate 14 carry, in spaced relation to the bushing 44, aligned bushings 55 and 56 respectively in which a shaft 57 is journaled. The shaft has thereon a collar 58 abutting the bushing 55 and a collar 59 abutting the bushing 56. Also carried on the shaft 57 is a worm gear 60 which is secured to the shaft by means of a pin 61.

The shaft 57 is stepped, and mounted on the stepped portion is a backing washer 62 and a roller 63, which are retained on the shaft by means of a screw 64. The roller 63 has a rim 65 of rubber-like material.

A bracket 66 has supported therein a roller, 66' which cooperates with the roller 41, and the axis of the shaft 67 of this roller is substantially on a vertical plane cutting the axis of the roller 41. The roller 66' preferably has a rim 68 of rubber-like material. The bracket 69 has supported therein a roller 70 which cooperates with the roller 52, and the axis of the shaft 71 of this roller is substantially on a vertical plane cutting the axis of the roller 52. The bracket 69 is identical with the bracket 66, and with another bracket to be presently described. Therefore, it is believed that a detailed description of one of the brackets is sufficient because the other two are duplicates of the same, so, this description is given in connection with the bracket 69 which may be seen in a section of elevation in Figure 5, and a side view as seen in Figure 1.

The bracket 69 has a portion 72 which is secured to the supporting wall 11 by means of screws 73, and dowels 74. Formed integral with the portion 72 is a horizontal portion 75 with spaced depending legs 76 and 77. The shaft 71 extends through a sleeve 78 which forms a hub of the roller 70 and is secured therein by means of a set screw 79. An elongated hole 80, formed in the leg 77 has, in alignment therewith, a second elongated hole 81 formed in the leg 76. The

roller 70 is a free roller which cooperates with the roller 52 under the urge of gravity, therefore, the weight of the roller 70 is important. This roller has a rim 82 of rubber-like material so that the film 83, engaged between the rollers 52 and 70, does not come in contact with the metallic surfaces of any roller.

A bracket 84, identical with the brackets 65 and 69, has supported therein a roller 85 which cooperates with the roller 63, and the axis of the shaft 86 of this roller is substantially on a vertical plane cutting the axis of the roller 63. The roller 85 preferably has a rim 87 of rubber-like material.

A U-shaped conduit 88 has an inlet leg 89 and an outlet leg 90. The axis of the inlet leg is preferably below and substantially in line with the line of contact between the rollers 20 and 30, and the axis of the outlet leg 90 is adjacent to the surface of the left side of the roller 41 (as seen in Figure 1). The U-shaped conduit is supported on the supporting wall 11 as follows: A bracket 91 embraces the conduit near the mouth of the left leg and this bracket is secured 25 to the supporting wall 11 by means of screws 92; a second bracket 93, which may be identical with the bracket 91, embraces the left leg 89 of the conduit in spaced relation to the bracket 91 and is secured to the supporting wall 11 by the screws 30 92. A bracket 94 embraces the leg 90 near the mouth thereof and is secured to the wall 11 by means of the screws 92. The lower end 95 (of the U-shaped portion per se) of the conduit 88 extends into a receptacle 96. This receptacle is 35 removably supported in the cabinet 10 on a plate member 97 which is secured to a horizontal partition 98 by means of wing bolts 112, and which has a portion 97a which extends through an opening 99 in said partition and forms a resting 40 place for the container 96.

Mounted on the vertical wall 11 is an angle bracket 100a which is secured thereto by means of screws 101a, and secured to the horizontal portion of this bracket is a mounting plate 102a of a pump 103a. The pump has a boss 104a which extends rearwardly through a hole 105a formed in the vertical wall 11, and the shaft of the pump may have secured thereto a grooved pulley 106a.

A second U-shaped tube 107 is identical with the U-shaped tube 88. It has a vertical inlet leg 108 and a vertical outlet leg 109. These legs are joined by a U-shaped portion 110 to form a unitary structure, and the U-shaped portion 110 extends into a receptacle 111 which is identical 55 with the receptacle 96. The receptacle 111 also rests on the plate 97 so that by removing the wing bolts 112 the plate may be lowered with both the receptacle 96 and the receptacle 111 resting thereon. The inlet legs 89 and 108 both have apertures 113 formed therein near the top thereof and embracing the legs about the apertures are casings 114a and 114 respectively. Since the leg 89 of the tube 88 is shown in elevation, the casing 114a mounted thereon is also shown in elevation, and the leg 108 of the tube 107 is shown in section; the casing 114 thereof is shown in section. The casings 114a and 114 are secured to the respective legs 89 and 108 in fluid-tight relation both above and below the apertures 113, and a pipe 115 has its upper end connected to the casing 114. A like pipe 115a is connected to the casing 114a. The lower end of the pipe 115a is connected to the discharge port 116a of the pump 103a and therefore by the fluid pumped by the pump 103a is delivered

into the casing 114a and it enters the leg 88 via the apertures therein like the apertures 113.

A tubular casing 117a embraces the leg 90 of the U-shaped conduit 88. It has its lower end preferably extending below the level of the upper rim of the receptacle 96, and its upper end is in the form of a flare 118a. Likewise the leg 109 of the U-shaped conduit 107 is embraced by a tubular member 117, the lower end of which extends below the upper surface of the receptacle 111, and the upper end of which has a flare 118 formed thereon. Formed in the leg 109 near the top thereof, are perforations 119, and like perforations 119a are formed in the leg 90 of the U-shaped tube 88.

The pipe 115a delivers fluid from the pump 103a via the casing 114a and the perforations 113a, and this liquid flows down the leg 89 around the U-shaped bottom of the conduit and up the leg 90 until it encounters the perforations 119a. These perforations allow the fluid to flow out into the flared portion 118a and thence the liquid flows downwardly between the tubular member 117a and the outer surface of the leg 90 and is delivered into the receptacle 96.

A pipe 120a extends below the liquid level in the receptacle 96 and has its upper end connected to the inlet 121a of the pump.

From the above it will be observed that there is a continuous circulation of the processing fluid from the receptacle 96 via the pump and via the pipe 115a and the casing 114a into the leg 89 of the U-shaped conduit, thence around the conduit in the direction of the movement of the film and outwardly through the perforations 119a into the flared portion 118a and thence downwardly within 117a to the tank.

The pipe 115 delivers fluid from the pump 103 via the casing 114 and the perforations 113. This liquid flows down the leg 108 around the U-shaped bottom of the conduit and up the leg 109 until it encounters perforations 119. These perforations allow the fluid to flow out into the flared portion 118 and thence downwardly between the tubular member 117 and the outer surface of the leg 109, and is delivered into the receptacle 111.

A pipe 120 connected to the inlet 121 of the pump 103 delivers liquid from the receptacle 111 to the pump thereby a continuous circulation of the processing fluid from the receptacle 111 is circulated in the manner described through the U-shaped tube 107.

A third U-shaped tube 122 is mounted on the wall 11 so as to be arrayed in alignment with the tubes 88 and 107. This tube is employed for washing the film after it has been processed in the preceding tubes, therefore, no pump is necessary if a source of water under pressure is available. The U-shaped tube 122 has a series of perforations 124 formed in its walls. A U-shaped water conduit 125 embraces the U-shaped tube 122 throughout its entire length, with the exception of a portion of the inlet leg 123 near the mouth thereof and a portion 126 of the outlet leg thereof. The tube 122 is secured within the U-shaped water conduit in any suitable manner and the combination is supported on brackets 122 and 123 which are mounted on the wall 11. The U-shaped conduit 125 has an enlarged portion 127 which is sealed to the inlet leg 123 in fluid tight relation at the point 128. The portion 127 has a pipe connection 129 communicating therewith and connected to this is a pipe 130 which terminates in a valve 131 below the hori-

zontal partition 98, and this valve is adapted to be connected to a source of water under pressure.

The right leg 132 of the U-shaped conduit 125 has its upper end enlarged to form an open tank or receptacle 133 and the right wall of this receptacle has a flared portion 134 which is positioned beneath the roller 63. A drain pipe 135 has its upper end threadedly engaging a boss 136 formed on the tank 133 and communicates with the interior of the receptacle 133. A ball float 137 normally rests on a seat formed adjacent to the boss 136. This ball is retained in this portion of the receptacle 133 by means of a cage 138. The lower end of the pipe 135 is adapted to be connected to a conduit for conveying the waste water away from the device. Where the pipes 130 and 135 pass through the horizontal partition 98 they are secured in shakeproof relation by means of interlocking threaded bushings 139. When the machine is set into motion the receptacles 96 and 111 have the necessary processing fluids therein and the valve 131 is open so that water will flow into the portion 121 of the U-shaped conduit 132, and this water flows both within the U-shaped tube and the U-shaped conduit entering the U-shaped tube via the perforations 124. Now, when the water passes around the U-shaped conduit and the U-shaped tube it enters the tank 133 and starts rising therein. When it has reached a level sufficient to raise the float 137, water may leave the receptacle 133 via the pipe 135. Thus the ball float arrangement makes sure that not less than a predetermined level of water is always present in the U-shaped tube 122 when the machine is operating.

Between the rollers 52 and 63 the wall 11 carries a boss 140 which has a hole therein threadedly engaged by a shouldered screw 141. Journaled on the shouldered screw 141 is a bracket 142 carrying a shouldered shaft 143 upon which a squeegee roller 144 is journaled, the roller being retained thereon by means of an end screw 145. The bracket 142 has a spring boss 146 thereon to which one end of a spring 147 is connected. The other end of the spring is connected to a post 148 on the wall 11, thus the bracket 142 and its roller 144 are urged upwardly so that the roller 144 squeegees water from the surface of the film leaving the leg 125 of the tube 122. The film, after it passes between the rollers 63 and the squeegee roller 144, encounters a guide member 149, which has a clearance opening formed therein for the roller 85, and passes between the rollers 63 and 85 and thence downwardly into a drying conduit 150. To insure the proper entrance of the film into the drying conduit a guide member 151 is provided in spaced relation to the guide 149 below the center line of, and to the right of, the roller 63 (as shown in Figure 1). Drying air is led into the drier via a passage 192. Since the drier per se forms no part of the present invention, as any good film drier may be used, it will not be described herein in detail. It is usual to supply such driers with warm air and, consequently, a blower and an air heater may be employed. The film 83, as it leaves the drier, encounters a drive roller 152 carried on a driven shaft 153 and having a rubber-like rim, and a cooperating free roller 154 which is journaled on a shaft 155 supported on a bracket 156 which is in turn journaled on a shouldered screw 157 supported in the wall 11. A spring 158 has one end connected to the bracket 156 and the other end secured to a post 159 extending from the wall 11.

Spaced apart from the rollers 152 and 154 is a take-up reel shaft 160 which carries a take-up reel 161. The end of the film is provided with a leader having several holes near the end thereof and these holes engage one or more of the hook members 162 provided on the hub of the reel. For guiding the end of the leader to the hooks a pivoted member 163 has aligned lugs 164 which are pivotally supported on the stud shaft 165 mounted in the plate 11. The member consists of a channel strip 166 having spaced pairs of lateral lugs 167 thereon; each pair of lateral lugs supports a shaft 168 and journaled on each shaft is a free roller 169. The film 83 passes down the channel and is retained therein by the rollers 169, and the pivoted member 163 is urged toward the reel by means of a spring 170 which has one end secured to the post 165 and the other end bearing against the pivoted member 163. A stop pin 171 mounted in the plate 11 is provided for limiting the swing of the pivoted member 163 in a counter-clockwise direction as seen in Figure 1. Now when the film 83 passes down the channel 166 and is engaged by one of the hooks 162 it begins winding up on the reel 161 and as the film builds up on the reel the pivoted member 163 is displaced toward the left or in a clockwise direction.

Mounted between the wall 11 and the support plate 14 is a reduction gear box 172 which has an input shaft 173 carrying a pulley 174. Extending 90 degrees with respect to the input shaft 173 are aligned output shafts 175 and 176. The shaft 175 is journaled in bearing brackets 177, secured to the plate 11, and 178 secured to the support plate 14. The bearing support 178 is positioned on the plate 14 so as to leave the clearance for the arm 17. The shaft 175 has secured thereto a worm which meshes with the worm gear 36. The shaft 176 is journaled in bracket bearings 181 and 182 which are secured to the plate 11, and the shaft 176 carries a worm 183 which meshes with the worm gear 49, and a worm gear 184 which meshes with the worm gear 60. The pulley 174 may be connected by means of a belt to a corresponding pulley on a motor, not shown, for driving the same and consequently driving the shafts 175 and 176 at a substantially slower rate and thereby causing the rollers 30, 41, 52 and 63 to rotate in unison.

The pumps 103 and 103a may be driven by a motor, not shown, having a pulley corresponding to and belted to pulleys 106 and 106a on the pumps 103 and 103a respectively. Since the pumps are driven at a high rate of speed no gear reduction is necessary for it is preferable to move the processing fluids at a substantial speed so as to wash off any deposits on the surface of the emulsion.

Referring to Figure 4, the processing and washing tubes 88, 107, and 122 may be formed of strip material in the form shown in Figure 4. One strip has spaced portions 185 and 186 the faces of which are in alignment. The strip also includes a portion 187 which is parallel to the portions 185 and 186. Joining the portions 185 and 187 is an annular portion 188 and joining the portions 186 and 187 is an annular portion 189. The portion 186 has a narrow web 190 the surface of which is substantially at right angles to the surface of the portion 186. Now when a second strip, in which the same portions bear the same numerals followed by the letter *a*, is positioned in cooperative relation with the first

strip, the portion 185a abuts the right angled portion 190 and the two edges are secured in fluid-tight relation by a line of welding 191. Likewise, the portion 185 of the first strip abuts the right angled portion 190a of the second strip and the two edges are secured together in fluid-tight relation by a line of weld 191a. When the tube is so formed the interior of the apex formed by the portions 189 and 188a clear the edge of the film 83 and likewise the inner apex formed by the portions 188 and 189a clear the right edge of the film 83. When the film is in position in the tube it divides the stream of processing fluid passing through the tube into two parts, as may readily be seen in Figure 4.

For guiding the film 83 into the inlet leg 89 of the U-shaped tube 88 a guide strip 193 has a rectangular opening formed therein through which the roller 20 extends, and a second guide strip 194 has a rectangular hole therein through which the roller 30 extends. These guide strips are secured to the inlet leg 89 and extend upwardly to a position where the end of the film may be inserted between them and engaged by the rollers 20 and 30.

For guiding the film from the outlet leg 90 of the tube 88 into the inlet leg 108 of the tube 107, the guide strip 195 is secured to said legs so as to guide the film onto the roller 41 as it leaves the leg 90. This guide strip has a rectangular opening formed therein through which the roller 66 may extend to contact the roller 41. A second guide strip 196 is secured to the adjacent faces of the legs 90 and 108 and has a rectangular opening through which a portion of the roller 41 extends so that film leaving the leg 90 passes between the guide strips 195 and 196 and passes over the roller 41 and between this roller and the roller 66, and thence into the inlet leg 108 of the tube 107. Between the outlet leg 109 and the inlet leg 123 guide strips which are identical with the guide strips 195 and 196 are provided, and since these are identical they are designated by the same numerals followed by the letter *a*.

What is claimed is:

1. In a film processor, a U-shaped conduit having its legs vertically disposed, film supporting and conveying means above the open ends of said legs for delivering film into the inlet leg of said conduit for pushing said film down said leg, around the bottom thereof and up the outlet leg thereof and for removing said film from the outlet leg thereof at substantially the same rate, a tank at least a portion of which is positioned below the level of the upper ends of said legs, a circulating pump having its inlet port connected to remove fluid from said tank having its outlet port connected to deliver said fluid into said inlet leg, and vertical overflow means carried on said outlet leg below the open end thereof via which fluid therefrom may return by gravity to said tank, said overflow means including a tubular guide embracing said outlet leg and extending into said tank.

2. In a film processor, a plurality of upright U-shaped conduits having their legs vertically disposed arranged in a series with film guides therebetween, means for supporting and for conveying and pushing a film through said conduits in a series of upright and inverted loops, at least two of said conduits having individual circulating means connected thereto for circulating processing fluid therethrough in the direction of movement of the film, thereby abetting the pushing effect by said first means overflow means on

each of said last mentioned conduits, and individual tubular guide means vertically disposed on and embracing the leg of each of said conduits having said overflow means therein to lead fluid therefrom to the respective circulating means.

3. In a film processor according to claim 2, in which each of said circulating means is individually interconnected with a tank for containing processing fluid, and in which each of said tubular guides insures the return of the overflow fluid to the tank associated with its respective circulating means.

4. In a film processor wherein a plurality of upright U-shaped conduits is arranged in a series, and in which means is provided for supporting and conveying film through all said conduits in a series of upright and inverted loops, one of said conduits forming a washing conduit and comprised of a U-shaped member, a second U-shaped member within said first member, said first member being imperforate and having means on its inlet end for connection to a source of water under pressure and having its outlet end substantially enlarged and carrying means therein for maintaining a constant liquid level therein, said second member having its walls perforate, whereby it functions to guide the film there through and to lay open both surfaces of the film to the washing action of the water, and overflow means connected to said enlarged portion of said first member.

5. A film processor according to claim 4, in which said means for supporting and conveying the film includes a drive roller having its face tangent to a plane extending through the outlet leg of said washing conduit, and in which a pivoted bracket carries a squeegee roller cooperating with and spring loaded toward said last mentioned roller so as to firmly engage the film and remove wash-water therefrom.

6. In a film processor, a plurality of upright U-shaped conduits arranged in a series with film guides therebetween, film supporting and conveying means between said conduits and said guides for pushing the film through said conduits and guides in a series of upright and inverted loops, individual circulating means connected to at least one of said conduits for circulating processing fluid therethrough in the same direction as the film is moved therethrough, thereby abetting the pushing action of said first means, a tank positioned beneath said last mentioned conduit and having the lower end of the latter extending into it, said circulating means including a pump having an inlet connection extending into said tank below the liquid level therein and having its outlet connected to deliver said fluid to one leg of said last conduit, and overflow means including a vertical tubular guide mounted on and embracing the other leg of said conduit for returning said fluid to said tank.

7. In a film processor, a casing having an inner vertical wall and a horizontal wall therebelow, a plurality of upright U-shaped conduits mounted on said vertical wall in a series with film guides therebetween, external film supporting and conveying means for pushing film through said conduits and said guides in a series of upright and inverted loops, a removable panel in said horizontal wall, an opening tank positioned on said panel and having the lower end of at least one of said U-shaped conduits ex-

tending into it, and circulating means for removing liquid from said tank and delivering it to the inlet leg of said last conduit so that it moves in the direction of movement of the film therethrough and abets the pushing action of said first means, and overflow means on and comprising a vertical tubular guide embracing the exit leg of said last conduit at least below the upper end of said tank for returning said fluid to said tank, said panel being adapted to be removed so as to lower said tank to a point beneath said horizontal wall.

8. In a film processor, a U-shaped conduit, film supporting and conveying means for delivering film into the inlet leg of said conduit, pushing the film through the conduit and for removing film from the outlet leg of said conduit at substantially the same rate, an opening tank positioned below the levels of the upper ends of said legs, a circulating pump connected to receive fluid from said tank and to deliver fluid to one leg of said conduit, overflow means on the other leg of said conduit via which fluid therefrom may return by gravity to said tank, said last means including a series of perforations formed in said last mentioned leg near the upper end thereof and a vertical tubular guide embracing said last leg and having its upper end adjacent to said perforations enlarged to receive fluid leaving said last mentioned leg via said perforations, and individual motor means for driving said circulating pump.

9. In a film processor, a U-shaped conduit, a U-shaped member within said conduit having its walls perforate thereby providing free communication between the interiors of said conduit and said member, means to convey a film through said U-shaped member, connections between one end of said conduit and a source of fluid, and overflow means connected to the other end of said U-shaped conduit whereby both surfaces of the film are freely contacted by said fluid via the perforated wall of said member.

10. In a film processor, a U-shaped conduit, a U-shaped member within said conduit having its walls perforate thereby providing free communication between the interiors of said conduit and said member, means to convey a film through said U-shaped member, connections between one end of said conduit and a source of washing water, and overflow means connected to the other end of said U-shaped conduit whereby both surfaces of the film are freely contacted by the wash water via the perforated wall of said member.
